UNITED STATES PATENT OFFICE

2,493,106

GEAR WHEEL

Jahue C. Burton, Hartsville, S. C.

Application March 26, 1947, Serial No. 737,211

2 Claims. (Cl. 74—448)

1

This invention relates to new and useful improvements in gear wheels and the primary feature of the present invention is to provide a sectional gear wheel made up of a number of parts and bolted together so that any damaged part may be quickly removed from the wheel and easily replaced without removing the entire wheel.

This invention is adapted to provide a sectional gear wheel particularly for looms, where in the use of looms a great stress is prevalent on the gear and its cogs are frequently stripped and to replace the gear other parts of the loom must be removed thereby making the loom idle and production time lost. The present invention therefore will provide a gear wheel whereby the stripped cogs are easily replaced in a minimum of time.

A further feature of the present invention is to provide a sectional gear wheel of the character referred to that reduces the normal expense of such a gear in operation as the replaced parts are cheaper than an entire gear.

A still further feature of the present invention is to provide a sectional gear wheel that is simple and practical in construction, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view of the improved gear wheel constructed in accordance with the present invention;

Figure 2 is a front elevational view of the gear wheel hub and spokes with the gear teeth plates removed therefrom;

Figure 3 is a fragmentary view showing the manner in which the gear teeth plates are secured to the hub;

Figure 4 is a sectional view taken on the line 4—4 of Figure 1, and

Figure 5 is a sectional view taken on the line 5—5 of Figure 1.

Referring now to the drawings in detail, wherein for the purpose of illustration I have disclosed a preferred embodiment of the present invention, the numeral 5 represents a preferably flat rim connected by integral radial spokes 6 to a hub 7, said hub having an internally formed oil groove 8 of conventional form.

A pair of semi-circular rings designated generally by the numeral 9 are substantially T-

shaped in cross section and the lower portion 10 of said rings opposing the outer face of rim 5 are held thereto by bolts 11 extending through openings 12 in the lower portion that engage threaded openings 13 in the rim. One flange 14 of said rings overlie the outer edge of rim 5 as shown in Figure 4 of the drawings.

Each end of rings 9 are cut away as at 15 to allow for true fitting of the bearing ends 16 at 10 each end of the rings.

Bolts 17 are fitted into internally threaded bosses 18 at each end of the rings for tightly connecting the rings to each other.

The rings 9 are formed with gear teeth 19 which are of conventional shape and spaced 15 equally apart from each other.

What I claim is:

1. A gear wheel comprising a flat annular rim, a hub having an internal oil groove, a plurality of flat spokes integrally formed with said rim and said hub and connecting the rim to the hub, an annular ring member including a plurality of arcuate sections substantially T-shaped in cross-section, each of said arcuate sections including an arcuate bearing portion and a flanged portion toothed at its outer surface, the flanged portions of said arcuate sections abutting and overhanging the outer edge of the rim, means for removably securing the bearing portions of said arcuate sections to one face of the rim, and means adjustably securing the arcuate sections to each other, the ends of said arcuate sections being notched to provide abutting bearing edges adjacent the notches.

2. The combination of claim 1, wherein said means adjustably securing the arcuate sections to each other includes a pair of spaced parallel attaching ears fixed to the arcuate sections adjacent the notched ends thereof, and an adjustable fastener connecting the ears.

JAHUE C. BURTON.
